IMPACT FIRING MECHANISM

Wilfred E. Thibodeau, Cleveland, Ohio, and
Gregory J. Kessenich, Madison, Wis.

Application January 24, 1941, Serial No. 375,797

14 Claims. (Cl. 102—76)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to projectiles in general and in particular to small arms and medium projectiles and impact firing means therefor.

The size of these smaller types of projectiles as well as the number employed precludes the use of the more complicated fuse structures and safety units therefor. Furthermore, in these types of projectiles precision fuses are not a necessity. All that is required is an impact firing device which will hold the projectile unarmed during storage and handling and while in the gun bore after firing. The firing device should be simple, low in cost, and easy of manufacture and assembly.

These requirements are fulfilled in the projectile of the invention which comprises a firing device having strikers which are immobilized by a matrix which may be processed in flight or on impact to free the striker and wherein the striker despite relaxation of the matrix continues immobilized during flight by the action of centrifugal force on its own mass.

It is, therefore, an object of this invention to produce a projectile having a firing device which is a centrifugal striker member.

It is another object of this invention to produce a projectile having a firing device with a centrifugal striker member and an immobilizing medium for said striker member comprising a material processible in flight or yielding on impact to free the striker. This material is an easily destructible, combustible, volatilizing or low fusing material. It may consist of a mixture of carbonaceous ingredients with a refractory material or other mixtures as described in Pat. No. 2,314,891.

It is a further object of the invention to produce a firing member comprising a plug which is radially contractile on impact.

To these and other ends, the invention consists in the construction, arrangement and combination of elements described hereinafter and pointed out in the claims forming a part of this specification.

A practical embodiment of the invention is illustrated in the accompanying drawing wherein:

Figure 1 is an elevation in section of the forward end of a projectile;

Figure 2 is a top plan view of the plug of Figure 1;

Figure 3 is a view similar to Figure 1 showing a modification.

Figure 4 is a section on the line 4—4 of Figure 3.

5 Figures 5 to 11 are elevations in section of the forward ends of projectiles, showing modifications of the plug firing device, and

Figure 12 is a top plan view of a projectile, showing a modification of the plug.

10 Referring to the drawing by characters of reference there is shown in Figure 1 a projectile body 1 with central cavity 2 and a threaded axial bore 3. Engaged in bore 3 is a threaded plug 4. Plug 4 is composed mainly of a fusible material 5, such as solder, and has harder metal inserts 6 forming a portion of the boundary surface of the plug including the threaded portion. The lower portions of inserts 6 have points 7 to serve as firing pins. Plug 4 is threaded in by means of spanner holes 8, so that the firing pin points 7 are spaced from the primer 9. Stop means may also be provided to space the points from the primer, such as a closed bottom thread in the bore 3. The primer may be held in any desired manner.

25 On firing, the heat generated by the friction of the projectile along the barrel rifling will serve to soften the solder 5, and this effect is increased by friction with the atmosphere during flight, reducing the solder to a more or less fluid condition

30 so that the steel inserts, 6, may be forced rearwardly against the primer. The movements of the inserts will not occur in the bore of the gun or during flight of the projectile, since centrifugal force will hold them engaged in the threads of bore 3. On impact the inserts 6 will be forced in, not by stripping of the threads, but by slipping radially inward and downward across the same, the barrier having been removed by combustion or volatilization, or rendered ineffective as a barrier, due to softening. Even if the barrier did not

35 soften appreciably in flight, the firing mechanism would function, because on impact the barrier would be squeezed in under the camming action of the threads or other taper. When the barrier member is a non-metallic member that is not processed or conditioned in flight, it is easily destroyed or driven rearwardly on impact. Such a yielding or shatterable material for example would be plaster of Paris, glass, cork and the like. The holding means need only be present in a shape or amount sufficient to maintain the inserts 6 in a position to engage the threads prior to the application of the centrifugal force, and in such case, where the spacer does not take up

40 45 50 55 the full cross-section of the bore, a cap may be

placed over the plug in the bore to keep out dust and moisture.

In Figure 3 is shown a solder plug 10 wherein the inserts 11 are two in number symmetrically disposed with respect to the plug and each insert has a cross section defined by an arc of the plug and its cord.

In Figure 5 the solder portions 12 and 13 are discs holding the steel pins apart at their upper and lower portions respectively.

In Figure 6 is shown a plug wherein the solder portion 14 is keyed into the steel pins by means of an annular flange 15.

In Figure 7 is shown a plug similar to that of Figure 6, but here instead of the steel members being firing pins they have connected thereto a central firing pin 16 with a cross bar head 17 slidably fitted in perforation 18 in the steel members.

In Figure 8 is shown a plug generally similar to that of Figure 7, but here the firing pin has a disc-like head 19 fitted in annular slots 20 in the steel members.

In Figure 9 is shown a plug generally similar to that of Figure 1 except that plug and primer have been preassembled into a threaded socket 21 for ready insertion into the projectile.

In Figure 10 is shown a plug generally similar to that of Figure 1. This plug has an additional safety in the form of lateral pins 22 engaging both the plug and the shell body. These may be of solder similar to that of the plug or they may be of steel as in the case of known types of centrifugal pins.

In Figure 11 is shown a plug force fit into a tapered bore 23 of the projectile body. This body is the same as that of Figure 1 except that the function of the thread is performed by the taper.

In Figure 12 is shown a plug consisting of two spaced striker members 24 having a circular periphery fitted to the opening in the shell and screwed or wedged therein. These members are held as a unit in spaced relation by a cross bar 25, which may be square or round in section or may be a long flat plate. The important feature is that the joining medium for the striker members need not occupy the full cross-section of the shell opening nor engage it. A dust and moisture cap may be provided. The joining member may be destructible by heat or only on impact.

We claim:

1. For insertion in the nose of a projectile, a plug comprising a matrix of a material structurally yieldable at the temperature encountered in gun fire and in flight, at least one striker member acentrically embedded in said matrix and comprising part of the lateral periphery of said plug, said member occupying less than one-half the cross-section of the plug, and radially extending means on the striker member for yielding interengagement with the projectile which continues while under the influence of centrifugal force to prevent longitudinal motion of the striker member until impact.

2. A plug for a projectile as in claim 1 in which said radially extending means comprise a slant surface.

3. A plug for a projectile as in claim 1 in which said radially extending means comprise threads.

4. A plug for a projectile as in claim 1 in which said striker member is a surface inlay in said matrix.

5. A projectile having an axial opening in the

give thereof and a plug in said opening, said plug comprising a matrix of a material structurally yieldable at the temperatures encountered in gun fire and in flight, at least one striker member acentrically embedded in said matrix and occupying less than one half of the cross-section of the plug, radially extending means on the striker member and complementary means in the said projectile opening for mutual yielding interengagement while under the influence of centrifugal force to prevent longitudinal motion of the striker member until impact.

6. A projectile as in claim 5 in which said interengaging means comprise surfaces slanted to diverge from the axis of the projectile in a direction forward thereof.

7. A projectile as in claim 5 in which said interengaging means comprise threads.

8. A projectile as in claim 5 in which said

20 striker member is a surface inlay in said matrix.

9. For insertion in the nose of a projectile, a

25 firing unit comprising an outer container, a primer in said container and a plug in said con-

tainer superimposed over said primer, said plug

30 comprising a matrix of a material structurally

yieldable at the temperatures encountered in gun

35 fire and in flight, at least one striker member

40 acentrically embedded in said matrix, and occu-

45 pying less than one half the cross-section of

the plug, radially extending means on the striker

50 member and complementary means on the inner

55 walls of the casing for mutual, yielding inter-

60 engagement while under the influence of centri-

65 ful force to prevent longitudinal motion of

the striker member until impact.

10. For use in a projectile, a plug comprising

a matrix of heat-destructible material, metal

striker inserts in said plug at the lateral periph-

70 eral boundary thereof, and laterally extending

means on said inserts for interengagement with

75 a projectile to prevent motion of said plug longi-

80 tudinally of the projectile, said inserts being

85 spaced from the center of said plug a sufficient

90 amount to permit escape of said inserts from

95 interengagement with the projectile by radially

inward motion after evanescence of said heat-

98 destructible material.

11. In combination, a projectile having an

100 axial nose bore, a plug in said bore comprising a

105 matrix of heat-destructible material, metal

110 striker inserts in said plug, and means in said

115 bore and on said inserts for interengagement

120 thereof to prevent motion of said inserts axially

125 of the projectile, said inserts being spaced from

130 the center of said plug a sufficient amount to

135 permit escape of said inserts from interengage-

140 ment with the bore by radially inward motion

145 after evanescence of said heat-destructible

150 material.

12. In a projectile having a bore, a plug com-

125 prising segments normally engaging the side

128 walls of the bore, and means thermally destruc-

133 tible upon firing and in flight for maintaining said

138 segments in yielding engagement with said bore,

143 said segments being movable radially inward of

148 said bore after destruction of said means, and

153 means between said plug and side walls opposing

158 sliding motion of said plug in said bore after de-

163 struction of said means and while still under the

168 influence of centrifugal force.

13. For insertion in a threaded bore in a nose

140 of a projectile, a plug comprising segments each

145 threaded in a manner to constitute one contin-

150 uous thread running from segment to segment.

for threadedly engaging the bore, and means thermally destructible upon firing and in flight forming a part of the plug and maintaining said segments in position to be threaded into the bore as one unit.

14. In a projectile having a bore in the nose thereof, a firing member comprising a metallic plug peripherally engaged in said bore in a manner to positively prevent sliding motion of said

5 plug in said bore and having interstices whereby to be radially contractile and whereby said plug is releasable from the engagement with the bore on impact by radially inward motion, and heat destructive means in said interstices normally holding said plug engaged in said bore.
